P. J. STANTON,
SELF OPERATING MINE DOOR FOR LOCOMOTIVES,
APPLICATION FILED, AUG. 18, 1920.

1,374,478.

Patented Apr. 12, 1921.

INVENTOR.
P. J. Stanton

A. Murphy BY ATTORNEY.

UNITED STATES PATENT OFFICE.

PATRICK J. STANTON, OF LUNDALE, WEST VIRGINIA.

SELF-OPERATING MINE-DOOR FOR LOCOMOTIVES.

1,374,478.

Specification of Letters Patent. Patented Apr. 12, 1921.

Application filed August 18, 1920. Serial No. 404,441.

To all whom it may concern:

Be it known that I, PATRICK J. STANTON, a citizen of the United States, residing at Lundale, in the county of Logan and State 5 of West Virginia, have invented certain new and useful Improvements in Self-Operating Mine-Doors for Locomotives; and I do hereby declare the following to be a full, clear, and exact description of the invention, such 10 as will enable others skilled in the art to which it appertains to make and use the same.

This invention relates to new and useful improvements in mine doors and has for its primary object the provision of means 15 whereby the doors may be automatically opened by a car or train passing through the door thereby obviating the necessity of employment of manual labor to open and close the doors.

Another object of this invention resides in 20 the provision of doors mounted to swing in either direction and equipped with tension means adapted to permit said doors to be freely opened by a train or car and which 25 will automatically close the doors after the passing of a train or car.

A further object of the invention is the 30 provision of guards applied to each side of the doors and adapted to be engaged by the train or car and which will protect and prevent the doors from being injured by being struck by the train or car.

A still further object of this invention is 35 the provision of a mine door of the above ~~stated~~ character, which will be provided with canvas loose connections between the rear or hinged edges thereof and the post to which the door is hinged, the door being of simple and efficient construction and of such 40 mounting that the door may be readily placed or removed, as desired.

With the foregoing and other objects in view as will be apparent as the description proceeds, the invention consists in the novel 45 construction, combination and arrangement of elements as more specifically set forth, claimed and shown in the accompanying drawings forming a part of the present application and in which:

Figure 1 is a front elevation, illustrating 50 a mine door constructed in accordance with my invention.

Fig. 2 is a longitudinal section on the 55 plane of line 2—2 of Fig. 1, looking in the direction indicated by the arrows, and showing a car at the door.

Fig. 3 is a detail enlarged transverse section through one of the car doors along the line 3—3 of Fig. 1.

Referring more in detail to the drawings 60 in which similar reference characters designate corresponding parts throughout the several views, 1 indicates a mine doorway having located therein side posts 2 to which are hinged doors 3 adapted to close the doorway 1 and overlie the track 4. The connections between the doors and posts are by means of strap hinges 5 secured to one of the sides of the doors and having eyelets in their ends to receive hooks 5 secured to the posts 65 2 whereby said doors are free to swing in either direction.

Coiled springs 7 are secured to the posts 2 and to one side of the doors 3 for the purpose of normally maintaining the doors in 75 closed position, but which will permit the doors to be swung in either direction when engaged by a train or car bumper 11 carried on a car 12, the bumper 11 being arranged so as to engage guards 8 mounted on the 80 sides of the doors 3. The springs 7 have their opposite ends mounted in the eyes formed in the ends of adjusting screws or screw eyes 7' which are extended through one angle of an angular supporting bracket 85 7'' mounted on the bolt 2 and the door 3 at suitable points, as shown in the drawings. Nuts 7''' are threaded upon the screw eyes 7' and contact with one face of the angular supporting bracket 7'' to retain the screws 90 in adjusted position and thereby regulate the tension of the springs 7.

The guards 8 are of substantially arcuate shape and have their opposite ends turned inwardly, as shown at 9 and secured to the 95 face of the door 3, by suitable bolts 10 passed therethrough. The arcuate guards 8 are arranged in pairs upon opposite sides of the door, as shown in Figs. 2 and 3.

Each door 3 has its end edge spaced from 100 and connected with the adjacent post 2 by a canvas or other flexible curtain member 13 extended in opposite directions and secured to the opposite edges of the post 2. This construction will also be readily apparent by 105 referring to Fig. 2 of the drawings.

It will be understood that a suitable cable 14 is extended through the doorway above one of the doors 3, a cable groove 15 being provided to accommodate the cable 14, as 110 clearly shown in Fig. 1 of the drawings.

From the foregoing paragraphs taken in

connection with the accompanying drawings, it will be seen that the bumper 11 carried by the car 12 will engage the arcuate guards 8 carried by the opposed doors and 5 force the same to swing upon the hinges ahead of the car as the latter passes through the doorway, the springs 7 serving to automatically return the doors 3 to closed position.

10 While the preferred embodiment of the invention has been shown and described, it will be understood that minor changes in the details of construction and arrangement of parts may be resorted to within the scope of 15 what is claimed without departing from the spirit of the invention.

Having thus described my invention what I claim is:—

1. A mine door comprising posts arranged 20 in the doorway of a mine, doors hinged to said posts and adapted to swing in opposite directions thereon, flexible connections between the hinged edges of said doors and said posts, means to resiliently retain said 25 doors in closed position, and guard members mounted on opposite sides of said doors for engagement by a locomotive to force said doors to swing to open position.

2. A mine door comprising posts arranged 30 in the doorway of a mine, doors hinged to said posts and capable of swinging in either direction, tension means connected to said doors for normally holding and returning said doors to a closed position, said doors 35 being adapted to be engaged by a train or car to open them, and a flexible member connecting the hinged edges of said doors and posts.

3. A mine door comprising posts arranged

in the sides of a doorway, doors hinged to 40 said posts and capable of swinging in either direction, coil springs attached to the posts and doors and upon each side of the doors for normally maintaining and returning said doors to a closed position, arcuate 45 shaped guards secured to each side face of said doors and adapted to be engaged by a train or car to open the doors, means for regulating the tension of said springs, and flexible connections between the hinged 50 edges of said doors and said posts.

4. A mine door comprising posts arranged in the sides of a doorway, doors hinged to said posts and adapted to swing in opposite directions thereon, guard members arranged 55 in pairs upon opposite sides of said doors, said guards having inturned ends with bolts secured therethrough and through said doors, said guards being of arcuate form and adapted to be engaged by a bumper carried by a car approaching said doors, said doors being adapted to be swung to open position as the car passes through said doorway, springs arranged in pairs upon opposite sides of said doors in closed position, 60 means for adjusting the tension of said springs, a track extended through said doorway, a cable extended through said doorway above said doors, and flexible connections between the hinged edges of said doors and 65 said posts.

In testimony whereof I affix my signature in presence of two witnesses.

PATRICK J. STANTON.
